CLAIM

The ornamental design for double cat tunnel hammock, as shown and described.

DESCRIPTION

FIG. 1 is a top, front, left side perspective view of a double cat tunnel hammock, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the double cat tunnel hammock in detached state; and,

FIG. 10 is an enlarged view of portion 10 in FIG. 2.

The evenly dashed broken lines illustrate portions of the double cat tunnel hammock and form no part of the claimed design. The dot-dash-dot broken lines define the boundaries of enlarged views and form no part of the claimed design.
